UNITED STATES PATENT OFFICE

GUY P. NORTON, OF MERIDEN, CONNECTICUT, ASSIGNOR TO THE MILLER COMPANY, OF MERIDEN, CONNECTICUT, A CORPORATION OF CONNECTICUT

DESIGN FOR A LIGHTING FIXTURE

Application filed December 19, 1929. Serial No. 33,836. Term of patent 14 years.

To all whom it may concern:

Be it known that I, GUY P. NORTON, a citizen of the United States of America, residing at Meriden, in the county of New Haven and State of Connecticut, have invented, a new, original, and ornamental Design for a Lighting Fixture, of which the following is a specification, reference being had to the accompanying drawing, forming a part thereof.

The figure is a side view of the lighting fixture, showing my new design. The ele-

ments of the present design are an upwardly flaring reflector and a lower plate or cup having a plain center and a fluted pie crust edge terminating in an ornamental nipple. The design has the same appearance when viewed from any side.

I claim:

The ornamental design for a lighting fixture as shown and described.

GUY P. NORTON.
